[57] CLAIM

The ornamental design for a moisture detector for a water control unit, as shown and described.

DESCRIPTION

FIG. 1 is a perspective view of a moisture detector for a water control unit showing my new design;

FIG. 2 is a front elevational view thereof;

FIG. 3 is a rear elevational view thereof;

FIG. 4 is an end elevational view thereof;

FIG. 5 is an end elevational view thereof;

FIG. 6 is a top plan view thereof; and,

FIG. 7 is a bottom view thereof.

The fragmentary broken line representation of an electric connector in FIG. 4 is for purposes of illustration only and forms no part of the claimed design.

FIG. 4

FIG. 1

FIG. 2

FIG. 6

FIG. 3

FIG. 5

FIG. 7
